UNITED STATES PATENT OFFICE.

THOMAS IRVINE, OF BEEF SLOUGH, WISCONSIN.

BOOM CHAIN AND PLUG.

SPECIFICATION forming part of Letters Patent No. 268,681, dated December 5, 1882.

Application filed July 22, 1882. (No model.)

To all whom it may concern:

Be it known that I, THOMAS IRVINE, a citizen of the United States, resident at Beef Slough, in the county of Buffalo and State of Wisconsin, have invented a new and valuable Improvement in Boom Chains and Plugs; and I do hereby declare that the following is a full, clear, and exact description of the construction and operation of the same, reference being had 5 to the annexed drawings, making a part of this specification, and to the letters and figures of reference marked thereon.

Figure 1 of the drawings is a representation of this invention in perspective, showing the 15 two plugs and the chain. Fig. 2 is a plan view, showing the ends of two logs with the chain and plugs attached. Fig. 3 is a perspective view of the same. Fig. 4 is a side view of one of the plugs. Fig. 5 is a plan view of the chain. 20 This invention has relation to means for connecting logs in rafting and booming; and it consists in the construction and novel arrangement of the beaded plugs, the offset neck-links engaging said plugs, and the intermediate connecting-link engaging the offset portions of the neck-links, all as hereinafter set forth.

In the accompanying drawings, the letters A and B indicate the ends of two logs.

C represents a metallic plug, preferably made 30 of wrought-iron. It is formed with a rounded concave neck portion, *d*, gradually swelling from the shank *e* to form the base of the head *g*. This construction is designed to give great strength to this part of the plug, which is often 35 subject to intense strain.

H designates a neck-link, fitting the shank of the plug easily, and having an offset bend,

k, at one side of sufficient depth to receive the end of a connecting-link, L, so that said link will never bind against the shank of the plug, 40 but will always be free to accommodate itself to any position which the logs may take with reference to each other.

In using this device a plug is driven through each neck-link into a log, so that the logs are 45 coupled securely, and yet have easy rolling play and a little endwise motion with reference to each other. As the connecting-link does not bind between the plugs and the neck-links, it will not wear out for a very long time, and 50 the device can be used therefore an indefinite number of times.

Eyebolts and T-bolts having threaded shanks have been used in connection with chains provided with rings for connecting the booms of 55 a raft prior to my invention, and neck-rings are old in boat-detachers. I do not therefore claim either broadly herein.

Having described this invention, what I claim, and desire to secure by Letters Patent, 60 is—

The log-coupling consisting of the headed plugs C, having the head *g* and concave *d*, the offset neck-links H, engaging said plugs, and the intermediate connecting-link, L, engaging 65 the offset portions *k* of the neck-links, substantially as shown and described.

In testimony that I claim the above I have hereunto subscribed my name in the presence of two witnesses.

THOMAS IRVINE.
